VELOCITY MODULATION TUBE

Jack W. Keuffel, Cambridge, Mass., assignor to
the United States of America as represented by
the Secretary of War

Application October 19, 1945, Serial No. 623,418

2 Claims. (Cl. 315—6)

1

This invention relates generally to electrical apparatus and more particularly to velocity-modulation electronic tubes.

In the operation of velocity-modulation tubes as high frequency oscillators or amplifiers it is many times desirable to alter the operating frequency. Generally, small frequency variations in such tubes are obtained by deformation of the resonant cavities associated with them. However, the variation of frequency obtainable by this means alone is limited and when a frequency variation beyond this range is desired, it is necessary to shift the electrical mode of operation such as may be obtained by completely changing the basic configuration of the associated frequency determining cavity or cavities. In velocity-modulation tubes which have the frequency-determining cavities external to the seal enclosing the evacuated portion of the tube, the usual procedure has been to remove the external cavity and replace it by a different type of cavity and thus make such tubes readily adaptable for operation over a wide range of frequencies.

It is an object of this invention to provide a tuning cavity for a two-gap, velocity-modulation, focused-beam oscillator tube in which the operating frequency is changed by reducing the drift tube transit time.

It is a further object of this invention to provide a means of reducing the drift tube transit time in a two-gap, magnetically-focused, velocity-modulation oscillator tube by employing a coaxial type cavity that will function when the drift tube transit time is reduced to a one-quarter cycle, thus permitting the operation of a high frequency velocity-modulation tube at frequencies other than those for which the tube was originally designed.

The requirement necessary to accomplish the above objects is met by replacing the usual wave-guide type cavity associated with velocity-modulation tubes by a coaxial line type cavity.

Other objects, features, and advantages of this invention will suggest themselves to those skilled in the art and will become apparent from the following description of the invention taken in connection with the accompanying drawings in which:

Fig. 1 is a diagrammatic representation of a tube and its associated cavity employing the principles of this invention;

Fig. 2 is an elevation showing the general physical configuration of the tube shown in Fig. 1; and

Fig. 3 is an elevation of the assembled tube and cavity shown in Fig. 1.

Referring now to Fig. 1, a velocity-modulation tube 10, including a glass envelope 11, a collector electrode 12, a cathode 13, a drift tube 14, buncher grid 15, and catcher grid 16, is connected to a

2

coaxial cavity 17, 17, consisting of inner conductor 18, 18 outer conductor 19, 19, and tuning plunger 20, 20. The physical configuration of the tube without the cavities attached is shown in more detail in Fig. 2. There the configuration of the metallic drift tube 14 is shown centered between grids 15, and 16.

Reference to Fig. 3 shows tube 10 assembled with coaxial cavity 17. A hollow box-like structure 21 provides means for holding tube 10 and coaxial cavity 17 in their proper assembled position so that the outer conductor 19 of coaxial cavity 17 is in electrical contact with the portions of both buncher disc 15 and catcher disc 16 which extend outside the glass envelope 11. Inner conductor 18 of coaxial cavity 17 is also held by means of structure 21 in contact with a portion of drift tube 14, which extends outside of glass envelope 11.

20 The usual circuit involving the use of a velocity-modulation tube of this general type operates with an associated frequency determining wave-guide type cavity of either cylindrical or rectangular shape. With a waveguide type external cavity connected to grids 15 and 16, the drift tube 14 is grounded and the tube with its associated frequency determining cavity operates at a frequency corresponding to the relation

$$\theta = N + \frac{3}{4}$$

30 where

θ is the electron bunch transit time in cycles, and N is any positive integer or zero.

With the arrangement of tube and cavity herein disclosed oscillations will occur when the electron bunch transit time follows the relation

$$\theta = N + \frac{1}{4}$$

40 This is due in part to the fact that the drift tube, instead of being grounded, is connected to the inner conductor of the coaxial cavity.

45 Adjustable short circuiting plungers 20, 20 are provided at each end of cavity 17 to vary the operating frequency for operation over the range with the electrical mode above defined.

With this arrangement herein disclosed, electrons passing the buncher grid 15 when it is at the maximum positive potential, proceed through drift tube 14, which is negative with respect to the buncher grid 15, and enter an intense radio frequency field between drift tube 14 and catcher grid 16 in which drift tube 14 is also negative with respect to catcher grid 16. Since the transit time of the electron bunches through drift space tube 14 follows the relation $\theta = N + \frac{1}{4}$, electron bunches will move through a retarding field between drift space tube 14 and the catcher grid 16, to deliver energy to the coaxial cavities and reinforce oscillations therein.

60 Thus, this arrangement of circuit elements per-

mits the drift space transit time to follow the relation $\theta = N + \frac{1}{4}$, rather than $\theta = N + \frac{3}{4}$, enabling a two-gap, velocity-modulation type tube to be operated over a different frequency range.

While there has been here described what is at present considered to be the preferred embodiment of the invention, it will be obvious to those skilled in the art that various changes and modifications may be made therein without departing from the scope of the invention.

What is claimed is:

1. In combination, a velocity modulation tube for producing oscillations at a very high frequency, comprising an electron emitting member, a buncher grid, a drift tube, a catcher grid, and a collector electrode, arranged in the order named, all of the foregoing elements of said tube having connections external thereto, a two-part coaxial transmission line disposed so that its axis is perpendicular to the axis of said tube, said tube being disposed between said parts, the outer conductor of said line being in contact with the external connections of said buncher and catcher grids, the inner conductor of said line being connected to the external connection of said drift tube, and a pair of means for respectively short-circuiting each part of said line, the transit time of the electrons in said drift tube in cycles being equal to $N + \frac{1}{4}$, where N represents zero or any positive integer.

2. In combination, a velocity modulation tube for producing oscillations at a very high frequency, comprising an electron emitting member, a buncher grid, a drift tube, a catcher grid, and a

10 collector electrode, positioned in the order named, all of the foregoing elements of said tube having connections external thereto, a two-part coaxial transmission line disposed so that its axis is perpendicular to the axis of said tube, said tube being disposed between said parts, the outer conductor of said line being in contact with the external connections of said buncher and catcher grids, the inner conductor of said line being connected 15 to the external connection of said drift tube, and a pair of plungers for variably short-circuiting the respective parts of said coaxial line, the transit time of the electrons in said drift tube in cycles being equal to $N + \frac{1}{4}$ where N represents zero or any positive integer.
